UNITED STATES PATENT OFFICE.

AXEL EMIL MÖLLER, OF COPENHAGEN, DENMARK.

DEVICE FOR SPINNING SCREW-FORMED WINDINGS OR CURLS OF HAIR OR LIKE MATERIAL.

1,114,016.

Specification of Letters Patent.

Patented Oct. 20, 1914.

Application filed September 10, 1913. Serial No. 789,054.

To all whom it may concern:

Be it known that I, AXEL EMIL MÖLLER, manufacturer, subject of the Kingdom of Denmark, residing at No. 5 Rosenborggade,

5 Copenhagen, Denmark, have invented certain new and useful Improvements in Devices for Spinning Screw-Formed Windings or Curls of Hair or the like Material; and I do hereby declare the following to be a 10 full, clear, and exact description of the invention, such as will enable others skilled in the art to which it appertains to make and use the same, reference being had to the accompanying drawings, and to letters or 15 figures of reference marked thereon, which form a part of this specification.

The present invention relates to an arrangement in connection with spinning machines for manufacturing curls, *i. e.* screw-formed windings of hair or the like material. By means of the said arrangement the material, after having been previously 20 twisted into a smooth cord, is through an excessive twisting (overtwisting) caused to 25 curl up so as to assume the shape of a screw-formed winding. The last portion of the spinning *i. e.* the curling process, which has up to the present been effected by hand, is now done automatically, which means saving 30 in labor and space.

The invention is shown on the accompanying drawing, in which—

Figure 1 shows the material in its three stages *viz.*, before spinning, spun into a 35 smooth cord, and curled up in screw-formed windings, and Fig. 2 shows a front view of the apparatus.

1, Fig. 2, is the material to be spun, corresponding to portion *a* in Fig. 1, and 2 is 40 the smooth twisted cord which is passed through the hollow axle 3 arranged to rotate in a bearing 4 and carrying a driving pulley 5. To the axle 3 is fixed a plate-shaped head on which are arranged a number 45 of pins, of which two, 7 and 8, are shown on the drawing. Upon these pins may be slipped rollers, sleeves or the like. The head 6 is further provided with a guiding device 9 for the smooth twisted cord issuing 50 from the hollow axle 3, the upper edge of said guiding device being about level with the centerline A—A of the apparatus. The guiding device may consist of a solid block or a suitably bent plate, a short piece of 55 tubing, a ring or the like. The smooth

twisted cord 2 is, after having left the hollow axle 3, carried over the pins 7 and 8 and thence over the guiding device 9 in the manner shown in Fig. 2.

Through the rotation of the axle 3 the material 2, Fig. 2, is twisted into a smooth cord corresponding to portion *b*, Fig. 1, and with the view of transforming this cord into the finished material which has the shape of a screw-formed winding, the special features of the invention consist partly in the arrangement of the guiding device 9 with its edge 10 at such a place in relation to the last guiding pin 8, that the direction of the cord between said pin and the edge 10 and the direction of the cord after having passed the edge 10, forms an angle of about 90°, and partly in the cord being immediately after having passed the edge 10 subjected to a hard twisting (overtwisting). Another 70 special feature consists therein that the finished material is wound upon a reel.

If desired, and for facilitating the process of curling, the edge 10 may be arranged at a small angle with the center line so as to impart to the cord a slight direction to one side. Immediately after leaving the edge 10 of the guiding device the cord is subjected to a further twisting as described below, and through this new twisting it will curl up 80 and assume the shape of a screw-formed winding as shown at 16, Fig. 2, corresponding to portion *c*, Fig. 1. After leaving the edge 10 the curled up material is carried through another hollow axle 12 arranged 85 to rotate in a bearing 11, a driving pulley 13 being fixed upon the said axle 12. To the axle 12 is attached a fork 14 whose prongs form bearings for a reel 15. When driving power is applied to the pulley 13 90 the axle 12 and with it the fork 14 and reel 15 will rotate, and through a device not shown on the drawing the reel is further arranged to turn on its own axis.

The extremity of the cord is secured to the 100 reel 15, and the axle 12 is made to rotate at a speed somewhat greater than that of the axle 3. As the curls or windings of the cord are formed the material will move forward quite automatically and be taken up 105 by the reel.

It is not absolutely necessary that the above described arrangement, by means of which the cord is carried at approximately a right angle over the guiding device, should 110

be fixed to the axle 3. A previously smooth twisted cord can for instance be wound on a suitable reel and thence be carried to an independent device provided with the guiding means for carrying it at approximately 90° over the edge of the guiding device in the same manner as described above, the said guiding device being in this case stationary.

10 I claim:—

1. In a device for curling hair and like material, the combination with a hollow curling shaft, of guides, for the twisted uncured portion of the material to be curled, situated approximately in line with the longitudinal axis of said shaft and at approximately right angles to the latter.

15 2. A device for curling hair and like material comprising a hollow rotatable shaft having its axis in alinement with the axis of the twisting member, a head carried by the latter, and guides on said head arranged to

feed the twisted material to said shaft and in a path at right angles to the longitudinal axis of the latter.

25

3. A device for curling hair and like material comprising a hollow rotatable member adapted to twist the material, a hollow rotatable shaft having its axis in alinement with the axis of the twisting member, a head carried by the latter, guides on said head arranged to feed the twisted material to said shaft and in a path at right angles to the longitudinal axis of the latter, and a storage reel for the curled material mounted 30 on the hollow shaft.

35

In testimony that I claim the foregoing as my invention, I have signed my name in presence of two subscribing witnesses.

AXEL EMIL MÖLLER.
